UNITED STATES PATENT OFFICE.

HERBERT O. RUSSELL, OF LOS ANGELES, CALIFORNIA, AND LAWRENCE J. EYLER, OF DAYTON, OHIO.

SPADE GRIP FOR MACHINE GUNS.

Application filed June 9, 1922. Serial No. 567,076.

To all whom it may concern:

Be it known that we, HERBERT O. RUSSELL and LAWRENCE J. EYLER, citizens of the United States, residing, respectively, at Los Angeles and Dayton, in the counties of Los Angeles and Montgomery and States of California and Ohio, have invented certain new and useful Improvements in Spade Grips for Machine Guns, of which the following is a specification.

This invention relates to spade grips for machine guns and relates particularly to a trigger mechanism for operating the sear of a machine gun.

The particular object of the invention is to provide in conjunction with the spade grip and handle of a machine gun, a trigger operable by the fore finger of the hand which grips the gun thereby producing greater accuracy of fire and leaving the left hand of the gunner free for other work.

With the above and other objects in view, the invention consists in the novel construction, combination and arrangement herein fully described, illustrated and claimed.

In the accompanying drawings;

Figure 1 is a fragmentary side elevation partly in section of a machine gun illustrating the spade grip and trigger mechanism.

Figure 2 is a top plan view of the same.

Figure 3 is an end view thereof.

1 designates a machine gun and 2 the spade grip thereof having the usual handle 3.

In carrying out the present invention, we arrange a trigger 4 in the upper portion of the space within the spade grip and extend a trigger guard 5 across said space for safety. The trigger is mounted on a pivot 6 and the forward portion or arm 7 of the trigger is laterally off-set as indicated at 8 in Figures 2 and 3, such off-set portion of the trigger cooperating with a plunger 9 which is arranged in the path of the trigger arm 8 and which is retracted to the normal position shown in Figure 1 by means of a retracting spring 10.

The opposite end of the plunger 9 cooperates with and actuates a transmission lever 11 which is mounted upon a pivot 12 in the lower part of the gun. The inner end of the transmission lever 11 cooperates with the short arm 13 of a sear operating lever 14 mounted on a pivot 15. The extremity

of the sear operating lever 14 is arranged 55 in cooperative relation to a sear operating slide 16 the operation of which will cause a corresponding operation of the sear slide of the gun.

It will be noted that the trigger is incorporated with the spade grip in such a way that it may be operated readily by the fore finger of the hand which directs the aim so that the other hand of the operator will be free.

Having thus described our invention, we claim:

1. The combination with spade grip of a machine gun, of a trigger pivoted in the upper portion thereof, a plunger in the path 70 of said trigger and adapted for actuation thereby, a sear operating lever, and a transmission lever having one arm in the path of said plunger and the other arm in co-operative engagement with the sear operating lever.

2. The combination with spade grip of a machine gun, of a trigger pivoted in the upper portion thereof, a spring retracted 80 plunger in the path of said trigger and adapted for actuation thereby, a sear operating lever, and a transmission lever having one arm in cooperative engagement with the sear operating lever.

3. The combination with spade grip of a machine gun, of a trigger pivoted in the upper portion thereof, a plunger in the path 90 of said trigger and adapted for actuation thereby, said plunger being offset to one side of the center of the gun, a sear operating lever, and a transmission lever having one arm in the path of said plunger and the other arm in cooperative engagement with the sear operating lever.

4. The combination with spade grip of a machine gun, of a trigger pivoted in the upper portion thereof, a trigger guard bounding the trigger operating space, a plunger in the path of said trigger and adapted for actuation thereby, a sear operating lever, and a transmission lever having one arm in the path of said plunger and the other arm in cooperative engagement with the sear operating lever.

In testimony whereof we affix our signatures.

HERBERT O. RUSSELL.
LAWRENCE J. EYLER.
